UNITED STATES PATENT OFFICE

HAROLD H. ROBINSON, OF OPALOCKA, FLORIDA, ASSIGNOR TO CURTISS AEROCAR COMPANY, INC., OF OPALOCKA, FLORIDA, A CORPORATION OF FLORIDA

DESIGN FOR A COMBINED TANK TRAILER AND TRACTOR

Application filed August 13, 1932. Serial No. 44,600. Term of patent 14 years.

To all whom it may concern:

Be it known that I, HAROLD H. ROBINSON, a citizen of the United States, residing at Opalocka, in the county of Dade and State of Florida, have invented a new, original, and ornamental Design for a Combined Tank Trailer and Tractor, of which the following is a specification, reference being had to the accompanying drawings, forming part thereof.

In the drawings:

Fig. 1 is a side view of the combined tank trailer and tractor;

Fig. 2 is a rear view thereof; and

Fig. 3 is a top view thereof.

The present design comprises as the principal and dominating feature thereof a relatively long horizontally disposed tank trailer body supported by wheels at its rear portion and having a V-shaped forward end in overlapped and superposed relation on the rear part of a tractor vehicle for support thereon.

I claim:

The ornamental design for a combined tank trailer and tractor, substantially as shown and described.

HAROLD H. ROBINSON.
